UNITED STATES PATENT OFFICE.

FRED ZIELKE, OF MARSHFIELD, WISCONSIN, ASSIGNOR, BY DIRECT AND MESNE ASSIGNMENTS, TO GEORGE SEUBERT, OF SAME PLACE.

AUTOMATIC STOP FOR MACHINES.

SPECIFICATION forming part of Letters Patent No. 629,883, dated August 1, 1899.

Application filed March 4, 1898. Renewed June 19, 1899. Serial No. 721,149. (No model.)

To all whom it may concern:

Be it known that I, FRED ZIELKE, a citizen of the United States, and a resident of Marshfield, in the county of Wood and State of Wisconsin, have invented certain new and useful Improvements in Automatic Stops for Machines; and I do hereby declare that the following is a full, clear, and exact description thereof.

10 My invention has for its object to improve the automatic stop for machines set forth in United States Patent No. 567,435, of September 8, 1896; and it consists in certain peculiarities of construction and combinations of parts hereinafter specified with reference to the accompanying drawings and subsequently claimed.

Figure 1 of the drawings represents a perspective view of my improved automatic stop mechanism; Fig. 2, a plan view of the same, partly in horizontal section; and Fig. 3, a detail transverse sectional view indicated by line 3 3 in the preceding figure.

Referring by letter to the drawings, A represents a drive-shaft having a belt-pulley B loose thereon; but instead of a belt-pulley any suitable driver for transmitting rotary motion may be employed. The hub of the belt-pulley or driver is provided with an annular groove in which a split friction-band C is arranged, this band being provided with lateral wedge-lugs b b', that engage corresponding recesses in ends of levers D D', these levers being in pivotal connection with ears c of a collar E, fast on another shaft F, in line with the former shaft and having rotation in standards d, rising from a base-plate G, pins e, extending from one side of said collar, being engaged with ears f of another

40 collar H, fast on said former shaft. The free ends of the levers D D' are in opposition to one conical end of a slide I, loose on shaft F, and a shifter J, in spanner connection with an annular groove g in the slide, 45 is adjustably secured on a rod K, loose in guides h, that extend upward from the aforesaid base-plate. The other (also conical) end of slide I operates free ends of levers L L', in pivotal connection with ears i of a stationary 50 support M, in which the shaft F revolves, the

other ends of these levers being provided with suitable recesses engaged by wedge-lugs j j', extending from a split friction-band N, engaging a collar P, fast on said shaft, it being understood that said support is a fixture on the base-plate of the machine, but owing to peculiarity of shape its lower portion is hid in Fig. 1. The latter friction-band is best illustrated in Fig. 3 and is the counterpart of friction-band C, one of the wedge-lugs of each band being split and the other solid. Therefore the levers D' and L' are not absolutely essential, their utility in the present construction and arrangement of parts being to balance the other levers D L, with which they are paired.

One end of rod K has a head k, and a spiral spring K' is arranged on said rod intermediate of a guide h and said head. In connection with the other end of the rod is a preferably flexible pull K'', designed for connection with a lever or treadle within easy reach of the operator of the machine to which my improved automatic stop mechanism is applied.

In pivotal connection with one of a pair of standards m, rising from the base-plate G, is a preferably spring-controlled latch Q for engagement of a notch n in the rod K, and it is preferable to have a hand-pull p in connection with the latch.

Fast on shaft F is a worm R, in mesh with a worm-wheel S, that is rigid on a spindle T, that has rotation in the standards m, and contained within a partly-round flange S' of the worm-wheel is a split friction-band U, the extremities of this band being in the form of wedge-lugs r, that engage a corresponding recess in a block t, arranged between the parallel straight extremities of the worm-wheel flange. The block t is opposed by a screw u in a lever V, fulcrumed to the aforesaid flange extremities and extended through the worm-wheel to have working contact with a cone W, that is loose on the aforesaid spindle. A horizontal bell-crank in pivotal connection with a base-plate standard V has one arm X in spanner connection with cone W, and the other arm X' of this bell-crank is shown between a pair of pins w, extending

from the shifter J, whereby movement of the latter with rod K in either direction will be communicated to said bell-crank.

- Engaging the friction-band U is one end of the hub of a pulley Y, normally loose on spindle T, and fast to the pulley is one end of a flexible hanger x for a weight Z of suitable dimensions. Adjustably secured on the other end of the pulley-hub by means of a set-screw y is the ring end z of a cam-trip Q' for the latch Q above specified. A pin d', extending in from one of the standards m, comes in the path of a peripheral lug e' on pulley Y to stop rotation of the latter when under power of weight Z, in flexible connection therewith, and the set of cam-trip Q' with relation to the pulley-lug determines the duration of action by a machine to which my automatic stop mechanism is applied.
- The automatic stop mechanism above described is especially designed for use in connection with machines for weaving spring-wire mattresses; but it may be found applicable to a variety of machines for different purposes.

In practice when the rod K is pulled out to contract spring K' and at the same time operate shifter J to move the double-cone slide I against the levers D D' the friction-band C will be clamped tight on hub of rotary driver B, and thus motion will be imparted to the coupled shafts A F and other parts of the machine embodying the herein-described mechanism. The latch Q engages notch n in rod K to hold the latter in adjusted position, movement of this rod and the shifter J, fast thereon, having operated the bell-crank to move cone W on spindle T in opposition to lever V, whereby depression of block t is had to tighten friction-band U, and thus insure rotation of pulley Y, with the worm-wheel S in mesh with worm R of shaft F aforesaid. The screw u is adjusted to take up wear and regulate contraction of the friction-band U on the hub of the aforesaid pulley. Rotation of pulley Y causes lift of weight Z and brings the cam-trip Q' into operation against latch Q to disengage the latter from rod K, whereby spring K' is free to expand and move said rod in a direction reverse to that previously described. This reverse movement of the rod operates the shifter J to move slide I away from levers D D' and against levers L L', whereby the grip of friction-band C is released from pulley B and friction-band N drawn tight on collar P to stop rotation of the latter and shaft F, to which it is secured. At the same time the bell-crank, in connection with cone W, is operated to slide the latter on the spindle away from lever V, whereby the grip of friction-band U is released from hub of pulley Y, and the power of the descending weight Z operates to rotate said pulley in the direction necessary to bring the cam-trip Q' to normal position, the pulley-lug e' coming into the stop d' in its path.

At any time it is desirable or necessary the

hand-pull p may be operated to effect lift of latch Q and stop of the machine.

As previously stated, the automatic stop mechanism is particularly designed for use in connection with spring-wire-mattress-weaving machines, and the set of the cam-trip with relation to the pulley-lug determines the length of wire run by the weaving-machine before the latter is automatically stopped.

The automatically-adjustable cone W, lever V, clamp-block t, friction-band U, and pulley Y constitute a clutch controlled by the bell-crank co-operative with the aforesaid slide-shifter, and there may be considerable variation of this clutch. It is also to be understood that the auxiliary shaft F is practically a continuation of the drive-shaft and that a suitable spring may be utilized in place of the flexible hanger and weight herein set forth.

Having thus described my invention, what I claim as new, and desire to secure by Letters Patent, is—

1. The combination of a shaft, a rotary driver loose on the same, another shaft coupled to the one aforesaid in line therewith, a collar fast on the auxiliary shaft, a friction-band on the collar, a similar band on the hub of said driver, a double-cone slide on the shaft continuation intermediate of said pulley and driver, a spring-controlled pull-rod, a latch for the same, a slide-shifter in connection with said rod, clamp-levers for the friction-bands arranged to be alternately actuated by said slide, a clutch, a clutch-controlling bell-crank, co-operative with the slide-shifter, a latch-tripper carried by a section of the clutch, and suitable means for imparting independent reverse movement to the trippe-carrying clutch-section.

2. The combination of a shaft, a rotary driver loose on the same, another shaft coupled to the one aforesaid in line therewith, a collar fast on the auxiliary shaft, a friction-band on the collar, a similar band on the hub of said driver, a double-cone slide on the shaft continuation intermediate of said pulley and driver, a spring-controlled pull-rod, a latch for the same, a slide-shifter in connection with said rod, clamp-levers for the friction-bands arranged to be alternately actuated by said slide, a clutch, a clutch-controlling bell-crank co-operative with the slide-shifter, a latch-tripper in adjustable connection with a section of the clutch, and suitable means for imparting independent reverse movement to the trippe-carrying mechanism.

3. The combination of a shaft, a rotary driver loose on the shaft, another shaft coupled to the one aforesaid, a collar fast on the auxiliary shaft, a friction-band on the collar, a similar band on the hub of said driver, a double-cone slide on the shaft continuation intermediate of said pulley and driver, a spring-controlled pull-rod, a latch for the same, a slide-shifter in connection with said rod, clamp-levers for the friction-bands arranged to be alternately actuated by said

slide, a spindle in gear with said shaft continuation, a pulley loose on the spindle, a latch-tripper in connection with the pulley, a friction-band on the pulley-hub, a clamp-lever for the latter friction-band, a lever-actuating cone loose on said spindle, a bell-crank connecting the latter cone with the aforesaid slide-shifter, and suitable means for imparting independent reverse movement to the 5 tripper-carrying mechanism.

4. The combination of a shaft, a rotary driver loose on the same, an auxiliary shaft coupled to the one aforesaid in line therewith, and provided with a rigid collar, a friction-band on the collar, a similar band on the 15 driver-hub, a double-cone slide on the auxiliary shaft intermediate of said pulley and driver, a spring-controlled pull-rod, a latch for the same, a slide-shifter in connection 20 with said rod, clamp-levers for the friction-bands arranged to be alternately actuated by said slide, a clutch, a clutch-controlling bell-crank, coöperative with the slide-shifter, a latch-tripper carried by a section of the 25 clutch, and suitable means for imparting independent reverse movement to the tripper-carrying clutch.

5. The combination of a shaft, a rotary driver loose on the same, another shaft coupled to the one aforesaid in line therewith, a collar fast on the auxiliary shaft, a friction-band on the collar, a similar band on the hub of said driver, a double-cone slide on the shaft 30 continuation intermediate of said pulley and driver, a spring-controlled pull-rod, a latch 35

for the same, a slide-shifter in connection with said rod, clamp-levers for the friction-bands arranged to be alternately actuated by said slide, a spindle in gear with said shaft continuation, a pulley loose on the spindle, a latch-tripper having a ring end in adjustable 40 connection with the pulley-hub, a pulley-clutch, a clutch-controlling bell-crank in connection with the aforesaid slide-shifter, and suitable means for imparting independent au- 45

tomatic reverse movement to said pulley. 6. The combination of a shaft, another shaft coupled to the one aforesaid in line therewith, a rotary driver loose on the former shaft, a clutch mechanism for the auxiliary shaft, and 50 a similar mechanism for the driver, a spring-controlled pull-rod, a latch for the same, a shifter in connection with said pull-rod, an actuating device for said clutches in connection with the shifter, a bell-crank also in connection with the shifter, a clutch in connection with the bell-crank, a latch-tripper carried by a section of the latter clutch, and suitable means for imparting independent reverse movement to the tripper-carrying clutch-sec- 55 60

In testimony that I claim the foregoing I have hereunto set my hand, at Marshfield, in the county of Wood and State of Wisconsin, in the presence of two witnesses.

FRED ZIELKE.
